UNITED STATES PATENT OFFICE.

WILLIAM P. QUENTELL, OF NEW YORK, N. Y.

ADDING MACHINE.

Application filed May 11, 1925. Serial No. 29,457.

This invention relates to improvements in number setting up devices for adding machines and recording machines, the setting up mechanism being the mechanism that determines the distance which the parts concerned travel to register or print the number selected, such registering being effected by additional means after the setting up mechanism has come to rest in set up position.

An object of the invention is to simplify the mechanism referred to, thereby contributing to the simplicity of construction, more particularly of machines of comparatively small size and light weight.

Another object of the invention is to make the operation of a machine, employing a setting up device, other than what is known as a keyboard, easier for the operator by lessening the mental effort required in selecting and engaging the part of the machine necessary to effect the selected number reaching its operative position, thus also contributing to the speed of the machine.

The foregoing and other objects of the invention, together with means whereby the same may be carried into effect, will be best understood from the following description of certain forms or embodiments thereof illustrated in the accompanying drawings wherein the invention is embodied in an adding and recording machine. It will be understood, however, that the particular constructions described and shown have been chosen for illustrative purposes merely, and that the invention, as defined by the claims hereunto appended, may be otherwise practised without departing from the spirit and scope thereof.

In said drawings:

Fig. 1 is a vertical section showing certain parts of an adding and recording machine embodying the present invention.

Fig. 2 is a view of setting up members on line 2—2 Fig. 1 in direction of arrows.

Fig. 3 is detail view on line 3—3 of Fig. 2 in direction of arrows.

Fig. 4 is detail section view on line 4—4 of Fig. 3.

Fig. 5 is a view similar to Fig. 2 showing a modified construction.

Fig. 6 is a similar view illustrating further modification.

Fig. 7 is a view on the line 7—7 of Fig. 6 looking in direction of arrows.

Fig. 8 is a view similar to Fig. 7 showing a modified construction.

Referring to the drawings, the dotted line A Fig. 1 denotes the outline of the left side of the frame part, it being understood that a large part of the mechanism is within the side frames and that the machine will include at its right hand side a frame part corresponding to that denoted by the dotted line A.

Extending transversely of the machine near the lower edge of the side frame parts thereof, is a slotted bar 1 and further to the rear of the machine is a second transverse slotted bar 2, these bars in connection with other suitable parts, connecting the two side frame parts of the machine.

At the upper part of the side frame parts is another transverse slotted bar 3, which serves to hold in place the upright bars or posts and guides 4 and 5, the lower ends of which being supported respectively in the slotted bars 1 and 2.

A plate 6 has fastened to it the brackets 7 and 8 which form bearings for the plate when it is mounted on the upright post 4, and permit it being moved along the post 4, Figs. 1, 3, 4. Attached to the plate 6 at substantially right angle is a number segment 11 upwardly and downwardly movable on the guide 4 and bearing a series of numeral digits, in this instance 0 to 9. The plate 6 is in effect a setting up key and extends beyond the number segment 11 and the edges are in form of a rack having gear teeth 9, 13, which correspond with the series of numeral digits and the teeth 9 form stations to receive an object, a stylus, for instance, with which the plate may be moved down along the post 4 by the operator. The plate 6 may be called the setting up member for convenience in referring to it. The teeth 9 are preferably pointed so as to offer as much space as possible where the stylus enters.

The numeral digits on the number segment 11 or plate 6 are arranged vertically, that is, one above the other, and instead of all being in one line or column, they are staggered, as, all the odd numbers in the left column and all the even numbers in right column. Thus arranged the space between the numbers of a column is twice as large as it would be if all the odd and even figures were in one column and with such arrangement larger figures may be used in a compara-

tively small machine thereby making the reading of them easier and contributing to the speed of the machine. In machines now on the market where a stylus is used for setting up figures to be added, the numerals are all in one vertical line and as these machines are of small size, the numerals are also small and call for great care from the operator in selecting them. By making the teeth 9 pointed and arranging them at practically right angle to the number plate 11, a stylus 12 that is flat and bifurcated Fig. 4 is readily directed into the teeth with little mental effort by the operator and through the two prongs of the forked end is held against slipping out of the teeth sidewise.

Extending transversely of the machine in front of the setting up members 6 is a slotted bar 14, Figs. 1, 2, which serves as a stop for the stylus when the latter has moved the setting up member the desired distance, Fig. 1, 12 in dotted lines. The stop 14 prevents overthrow of the setting up member when it is moved rapidly, as the stylus between two teeth 9 and bearing on the stop 14 locks the setting up member against further movement downwards and the weight of the operator's hand prevents it rebounding after sudden stop and remaining in the rebound position. The slots insure that when the stylus is at the bottom of the angle between two teeth it will at that point also bear on the stop 14, so that the setting of each member or key 6 is accurate.

The member 6 may be provided with a lip or key-top 10 which can be used by the operator for depressing the member 6 when operating without a stylus.

The rear edge of the setting up member 6 is formed with gear teeth 13 which mesh with a gear wheel 21 mounted on a cross rod 22. These teeth or racks 13 constitute means for the positioning of printing mechanism. The gear 21 meshes with the teeth 20 of a shuttle 18 which is mounted on post 5 to slide up and down. The rear edge of the shuttle 18 is provided with rack teeth 19 which are engaged by an aligning pawl 15 pivotally mounted on cross rod 16 and held in contact with the teeth 19 through the spring 17, the function of the pawl 15 being to prevent accidental movement of the parts including the setting up member 6, which through its gearing to the shuttle 18 moves in unison with the shuttle.

A cross bar 23 forms a bail with its side parts 24 fastened to a shaft 25 which is mounted to rotate in the frame side parts, 60 A and extends outside of the frame parts. On the left end of the shaft 25 outside of the left frame side part is fastened an arm 26 carrying a pin or anti-friction roller 27. A shaft 28, also mounted to rotate in the 65 frame side parts and extending beyond said

side parts has fastened to it near the outer end a cam 29 which engages the pin 27, thus when the shaft 28 is rotated forwardly the cam bears on the pin 27 and causes the bail 23 to move upwards when the bail will move back to normal any setting up member that had been brought down to set up a number. An operating handle 30 Fig. 1 in dotted lines, is attached to the shaft 28 on the right hand side of the machine.

A number wheel 31 with its gear wheel 32 constitutes an adding wheel and the orders of said wheels constitute an accumulator which is carried in a rocking frame 33 pivoted at 34. Fig. 1. There is an adding wheel for each order, the whole constituting an accumulator. The wheel 31, by this number is meant the whole adding wheel, is brought into engagement with the teeth 9 of the setting up member 6 when the wheel frame 33 is oscillated at the proper time as is usual in adding machines. The mechanism for controlling and actuating the adding mechanism may be of any suitable or well-known construction and need not, therefore, be herein shown or described.

The shuttle 18 is provided with a rearwardly extending finger 18^a which carries a type bar or segment 35 pivoted at 18^b. In printing the type bar 35 is brought upward to the printing line opposite the platen 36 when the setting up member 6 is brought down to set up a number. As with the adding wheel, the type bar forms no part of this invention, therefore any well-known and suitable means may be used for effecting the printing without its being shown and described herein.

It will, of course, be understood that the single setting up member and co-operating parts, including the adding wheel and the type bar shown in Fig. 1 represent only one of several such elements or mechanisms of an adding and recording machine and that the complete machine will contain as many setting up members and co-operating parts as may be necessary according to the desired capacity of the machine.

The operation of the machine is as follows: Assuming that the numeral 7 is to be added and recorded, the operator inserts the stylus 12 in the space between two of the teeth 9 of the setting up member 6 which is in line with the Figure 7 on the number segment 11, then draws down the setting up member until the stylus is stopped against the cross bar 14, when the stylus is then removed. As the setting up member is moved downward its shuttle 18, being geared through gear wheel 21 to the member 6, will move upward and bring the type character corresponding to the number selected in the setting up parts to the printing position when the stylus is stopped against the cross bar 14. In the present instance the number 130

7. The aligning pawl 15 will hold the parts from accidental movement. On moving the operating handle 30 forward it will rotate the shaft 28 and cause the printing and the bringing of the adding wheel 31 into mesh with the teeth 9 of the setting up member 6. On further rotation of the shaft 28, the cam 29 will depress the arm 26 through the pin 27 and thereby raise the bail 23, which will pick up and push back to normal the setting up member 6 which had been set up for a. 7. During the ascent of the setting up member it will rotate the adding wheel 31 in adding direction. When the bail 23 has returned what setting up member that had been in set up position to normal position, the handle 30 may be returned to its normal position, during which travel it may throw the adding wheel out of mesh with the setting up member and accomplish any other functions that may be necessary.

In taking a total the gear wheels 32 are first thrown into engagement with the racks 9 in a known manner, and then each of the key elements 6 is depressed, preferably by means of the key-top or lip 10, which causes each adding wheel to be turned to zero, the wheels being stopped by the usual or suitable zero stopping means and then the parts are ready for the printing of the total, and when the accumulator is thrown out of engagement with the key elements it is in a cleared condition.

While I have shown and described an adding and recording machine employing sliding setting up members with the number segments attached to and movable with the setting up members and the rack or station part of the setting up member at substantially right angle to the number segment, my invention is not limited in this regard and these parts may be varied as, for instance, shown in Fig. 5 where the parts 37 are the equivalent of the teeth 9 of a setting up member and are in a plane with the number segment; Fig. 6 where the part 38 is the equivalent of comb or transverse bar 3 and the continuation 38^a is the equivalent of the number segment 11 and the further extension 38^b is the equivalent of the cross bar 14. In this construction the number segment 38^a is stationary and only the part 39, which is the equivalent of the setting up member 6, moves; Fig. 8 where part 40, 40^a, 40^b, is the equivalent of part 38, 38^a, 38^b of Fig. 7 and part 41 is the equivalent of the setting up member 6 and is pivoted at 42 instead of being mounted to slide on an upright post.

Having thus described my invention I claim and desire to secure by Letters Patent:

1. In a key-set adding machine, the combination of an accumulator, a transversely arranged series of orders of adding mechanism for said accumulator each having an

upwardly and downwardly movable rack member constituting a setting up key and having a front rack for engagement by a stylus, a vertical series of numeral digits related in position to the teeth of said front rack and arranged at the side of the same, a gear wheel on said accumulator adapted to be engaged with and to be disengaged from the lower part of said front rack; a stop bar extending transversely across said orders below said series of numeral digits and adapted to arrest a stylus, a bail and actuating means for restoring the set rack members to normal position.

2. In a key-set adding machine, the combination of an accumulator, a transversely arranged series of orders of adding mechanism for said accumulator each having an upwardly and downwardly extending and rearwardly inclined guide arranged at the rear of said accumulator, a rack member constituting a setting up key and slidably mounted on said guide and having a front rack to be engaged by a stylus, a vertical series of numeral digits related in position to the teeth of said front rack and arranged at the side of said rack member, a gear wheel on said accumulator adapted to be engaged with and to be disengaged from the lower part of said front rack; a stop bar for the stylus extending transversely across said orders below said series of numeral digits to arrest said stylus, a bail and actuating means for elevating said rack members to normal position, and means for holding said rack members in set position against accidental displacement.

3. In a key-set adding machine, the combination of an accumulator, a transversely arranged series of orders of adding mechanism for said accumulator each having an upwardly and downwardly extending guide arranged at the rear of said accumulator, a rack member constituting a setting up key and slidably mounted on said guide and having a front rack, a vertical series of numeral digits related in position to the teeth of said front rack and arranged at the side of said rack member, a gear wheel on said accumulator adapted to be engaged with and to be disengaged from the lower part of said front rack; a stop bar for a stylus extending transversely across said orders below said series of numeral digits, a bail and actuating means for restoring the set rack members to normal elevated position, the upper part of said front rack being engageable by a stylus to adjust the rack members to adding position and the stylus being then adapted to engage with said stop bar, and means for temporarily holding said rack members in adjusted position.

4. In a key-set adding machine, the combination of an accumulator, a transversely arranged series of orders of adding mecha-

- nism for said accumulator each having an upwardly and downwardly extending guide arranged at the rear of the accumulator, a rack member constituting a setting up key 5 and slidably mounted on said guide and having a front rack, a vertical series of numeral digits related in position to the teeth of said front rack and arranged on the said rack member, a gear wheel on said accumulator 10 tor adapted to be engaged with and to be disengaged from the lower part of said front rack; a stop bar extending transversely across said orders below said series of numeral digits and having slots receiving the 15 upper parts of the front racks of said keys, a bail and actuating handle for elevating said rack members to normal position, a stylus having a bifurcated front end adapted to be engaged at will with the upper 20 parts of said front racks to adjust the rack members to adding position and to be depressed to engagement with said stop bar, and means for holding said rack members in adjusted position.
- 25 5. In a key-set adding machine, the combination of an accumulator, a transversely arranged series of orders of adding mechanism for said accumulator each having an upwardly and downwardly extending guide 30 arranged at the rear of said accumulator, a rack member constituting a setting up key and slidably mounted on said guide and having a front rack, a vertical series of numeral digits related in position to the teeth of said 35 front rack and arranged on the said rack member with the odd digits in one vertical line and the even digits in another vertical line, a gear wheel on said accumulator adapted to be engaged with and to be disengaged 40 from the lower part of said front rack; a stop bar extending transversely across said orders below said series of numeral digits and having slots receiving the upper parts of the front racks of said keys, a bail and 45 actuating handle for elevating said rack members to normal position, a stylus having a bifurcated front end adapted to be engaged at will with the upper part of said front racks to adjust the rack members to adding 50 position and to be depressed to engagement with said stop bar, and means for holding said rack members in adjusted position.
6. In an adding machine in which the digits of an item are first set up and the 55 whole item is subsequently added at once, a setting-up device having in combination a series of number segments each bearing a series of numeral digits, a series of movable setting up members each having pointed rack 60 teeth forming a series of stations corresponding with the series of numeral digits and each station of said setting up member being adapted to receive an object for actuating its setting up member, said rack teeth projecting forward at substantially a right angle 65 to said numeral segment, said setting up members having at their tops key elements whereby they may be depressed, a stop bar extending transversely across said setting up members below said series of numeral digits, and means for holding said setting up members in adjusted position.
7. A stylus for the operation of adding machines having a handle and at its forward end a portion for engaging with the toothed setting-up racks of the adding machine, and having at each side of said portion a forwardly projecting part to be situated at the side of the rack when engaged by the stylus. 75
8. In an adding machine in which the digits of an item are first set up and the whole item is subsequently added at once, a setting-up device having in combination a series of number segments each bearing a series of numeral digits, a series of movable setting up members each having pointed rack teeth forming a series of stations corresponding with the series of numeral digits and each station of said setting up member being adapted to receive a stylus for actuating its setting up member, said rack teeth projecting forward at substantially a right angle to said numeral segment, a stop bar extending transversely across said setting up members below said series of numeral digits and having slots receiving the teeth of said setting up members, means for holding said setting up members in adjusted position, and a bifurcated stylus for engaging between 85 said teeth and at each side of said setting up members. 90
9. In an adding machine in which the digits of an item are first set up and the whole item is subsequently added at once, a setting-up device having in combination a series of number segments each bearing a series of numeral digits, a series of movable setting up members each having pointed rack teeth forming a series of stations corresponding with the series of numeral digits and each station of said setting up member being adapted to receive an object for actuating its setting up member, said rack teeth projecting forward at substantially a right angle 95 to said numeral segment, said setting up members having at their tops key elements whereby they may be depressed, a stop bar extending transversely across said setting up members below said series of numeral digits, and means for holding said setting up members in adjusted position. 100
10. In an adding machine in which the digits of an item are first set up and the whole item is subsequently added at once, a setting-up device having in combination a series of number segments each bearing a series of numeral digits arranged in vertical and staggered formation, a series of movable setting up members each having 105
- 110
- 115
- 120
- 125
- 130

- pointed rack teeth forming a series of stations corresponding with the series of numeral digits and each station of said setting up member being adapted to receive an object for actuating its setting up member, said rack teeth projecting forward at substantially a right angle to said numeral segment, said numeral segment being attached to and movable with said setting up member, a stop bar extending transversely across said setting up members below said series of numeral digits and having slots receiving the teeth of said setting up members, and means for holding said setting up members in adjusted position.
11. In a key-set adding machine, the combination of an accumulator, a transversely arranged series of orders of adding mechanism for said accumulator each having an upwardly and downwardly movable rack member constituting a setting up key and having a front rack for engagement by a stylus and provided with a key-top whereby the rack member may be depressed, a vertical series of numeral digits related in position to the teeth of said front rack and arranged at the side of the same, a gear wheel on said accumulator adapted to be engaged with and to be disengaged from the lower part of said front rack; a stop bar extending transversely across said orders below said series of numeral digits and adapted to arrest a stylus, a bail and actuating means for restoring the set rack members to normal position.
12. In a key-set adding machine, the combination of an accumulator, a transversely arranged series of orders of adding mechanism for said accumulator each having an upwardly and downwardly movable rack member constituting a setting-up key and having a front rack for engagement by a
- stylus and having a rear rack, a vertical series of numeral digits related in position to the teeth of said front rack and arranged at the side of the same, a gear wheel on said accumulator adapted to be engaged with and to be disengaged from the lower part of said front rack; a stop bar extending transversely across said orders below said series of numeral digits and adapted to arrest a stylus, a bail and actuating means for restoring the set rack members to normal position.
13. In a key-set adding machine, the combination of an accumulator, a transversely arranged series of orders of adding mechanism each having a rack member constituting an adding key and movable upward and downward and operable by means of the teeth of said rack, the lower part of said rack member being connectible with an order of said accumulator, a row of digits denoting the teeth of said rack, and means for stopping the rack according to the number of the tooth by which the rack has been operated.
14. In a key-set adding machine, the combination of an accumulator, a transversely arranged series of orders of adding mechanism each having a rack member constituting an adding key and movable upward and downward and operable by means of the teeth of said rack, the lower part of said rack member being connectible with an order of said accumulator, a row of digits denoting the teeth of said rack, said row having the odd and even digits respectively staggered to the right hand and to the left hand substantially as shown, and means for stopping the rack according to the number of the tooth by which the rack has been operated.

WILLIAM P. QUENTELL.
